UNITED STATES PATENT OFFICE.

JOHN COULSON, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTROLYTIC APPARATUS.

1,250,146.

Specification of Letters Patent. Patented Dec. 18, 1917.

Application filed January 6, 1917. Serial No. 140,925.

To all whom it may concern:

Be it known that I, JOHN COULSON, a subject of the King of Great Britain, and a resident of Wilkinsburg, in the county of Allegheny and State of Pennsylvania, have invented a new and useful Improvement in Electrolytic Apparatus, of which the following is a specification.

My invention relates to electrolytic apparatus, such as condensers, lightning arresters and the like, and it has for its object to provide a structure for such apparatus which shall include simple and effective means for supporting the active plates in proper relation to one another and to their container and which shall be so constructed and arranged that the active plates, their spacers and supports and all other attachments immersed in the electrolyte shall be composed of film-forming metal or shall have exposed surfaces of such metal.

According to my invention, I provide an electrolytic cell consisting of a series of parallel plates which may be either rectangular and vertically disposed or in the form of circular trays and which are composed of aluminum, magnesium or some other film-forming metal. The plates of the same polarity are rigidly fastened together by means of sets of spacers of film-forming metal which extend freely and without contact through openings provided in the plates of the other polarity. Each set of spacers constitutes, in effect, a continuous rod having all of the plates of one polarity rigidly attached thereto, and the ends of this composite rod are extended nearly to the sides of the container or are otherwise supported in such a manner that no greater degree of movement is permitted than is required for the formation of the asymmetric conducting films upon the plates. The entire plate structure is preferably suspended from the cover of the container, the effect being that the plates are held against substantial movement in any direction.

In the accompanying drawing, Figure 1 is a plan view, partially in horizontal section, of an electrolytic condenser constructed in accordance with my invention. Fig. 2 is a side view, partially in elevation and partially in section, of the structure shown in Fig. 1. Fig. 3 is a fragmentary sectional view, on an enlarged scale with respect to Figs. 1 and 2, showing the construction of

the spacing members employed in my device and their relation to the condenser plates. Fig. 4 is a vertical central sectional view of another form of electrolytic cell constructed in accordance with my invention, and Fig. 5 is a plan view, with the cover removed, of the cell shown in Fig. 4.

The condenser shown in Figs. 1, 2 and 3 of the drawings consists of a number of parallel plates 2 arranged in two sets of opposite polarity, the plates composing the two sets being alternated and spaced apart. The plates are inclosed within a container 3 which may be constructed of wood, porcelain, enamel-lined metal or any other material which is not affected by the film-forming electrolyte to be contained therein, or the entire container may be constructed of aluminum or other film-forming metal or may be lined with such metal. As best shown in Fig. 1, the plates are held rigidly in spaced relation by means of six sets of spacers, sets 4 and 5 having the additional function of suspending the entire set of plates from the cover 6 of the container 3 while the remaining sets of spacers 7, 8, 9 and 10 are extended to loosely engage the sides of the container and prevent substantial movement of the plates. The sets of spacers 7 and 8 are disposed near the upper edges of the plates while the sets 9 and 10 are disposed near the lower edges. The spacers must not be braced too tightly against the sides of the container, since the films which form on the plates cause the entire structure to expand slightly. In practice, I find that a clearance of about $\frac{3}{2}$ of an inch between the end spacers and the container wall is sufficient for this purpose.

Each set of spacers consists of a series of sections 11 of aluminum rod, each section being bored and tapped at one end and provided at the other end with a threaded extension 12 of the proper size to be fitted within the tapped opening of the adjacent spacer. As stated above, the spacers in each set coöperate to clamp and hold the plates composing one of the two sets of opposite polarity and are wholly out of contact with the other set of plates, this result being accomplished by providing aligned openings in all of the plates, the openings 13 in the alternate plates to be clamped by a given set of spacers being of such size as to fit over the threaded spacer ex-

tensions 12, while the openings 14 in the plates of the other polarity are of sufficiently larger diameter than the spacers 11 to insure that the spacers and such plates 5 will be out of contact when the parts are assembled.

The sets of spacers 7, 8, 9 and 10 are provided with end spacers 15 of the pointed and flanged form shown in Fig. 1, half of the end 10 spacers being provided with bored and tapped openings and the other half having screw-threaded extensions, in order to be fitted upon the ends of the spacer sets. The ends of the spacer sets 4 and 5 are attached, 15 by means of bolts 17, to suspension straps 18 which extend across the tops of the plates and are bent downwardly at the ends to engage the spacer sets. Similar straps 18 are associated with the spacer sets 7 and 8, and 20 all four of the straps 18 are centrally suspended from the cover 6 by means of terminal rods 19 which are secured to the central portions of the straps in any suitable manner and are provided with reduced portions 25 20 which extend through openings in the cover 6 and carry binding posts 21 and suitable tightening nuts and washers 22 and 23.

A pipe coil 24 may be suspended from the cover 6 for the purpose of circulating cooling fluid through the interior of the 30 container. The inlet and outlet portions of the coil 24 extend through openings 25 near the side edges of the cover 6, these openings being closed by plates 26 provided with openings 35 to receive the ends of the pipe 24. Connection between the terminals of the pipe 24 and outer supply pipes may be made through suitable flanges 27 which clamp a gasket 28 between them.

40 In the construction shown in the drawing, the tank 3 is lined with aluminum as shown at 30, and it is therefore necessary to provide means for insulating the end spacers 15 from one another in order that the plates of opposite polarity may not be short-circuited through the walls of the container and 45 through the spacers. For this purpose, I provide a wooden frame at each side of the tank, such frame comprising horizontal members 50 31 extending the full length of the tank and vertical cleats 32 between which the end spacers 15 are confined. The ends of the spacers 15 rest against the horizontal members 31 and are thereby mechanically braced 55 and electrically insulated from one another.

In assembling the condenser which I have shown and described, the several spacer sets and the stack of plates are simultaneously built up, each plate being laid over the 60 screw-threaded extensions of the spacers which are already in place and additional spacers being added and screwed tightly in place to firmly clamp the plate. When all of the plates and spacers have been assembled 65 in this manner, the end spacers 15 and

the suspension straps 18 are attached to the ends of the spacer sets, and the entire plate structure is attached to the cover 6 by means of the terminal rods 19. The condenser is completed by lowering the plates into the 70 container 3, with the end spacers 15 inserted into the proper grooves between the cleats 32, a suitable quantity of film-forming electrolyte having previously been placed in the container 3. 75

It will be observed that, when the parts are assembled in the manner described, the condenser plates are prevented from substantial movement in any direction, since the end spacers 15 are confined by the walls of 80 the container 3 or by the frame members 31 and are prevented from lateral movement by the cleats 32, while vertical movement of the plates is prevented by the suspension straps 18 and the terminal rods 19. It will 85 also be observed that all of the parts which are associated with the condenser plates and immersed in the electrolyte are composed wholly of aluminum or of such other film-forming metal as is employed. If desired, 90 the spacers 11 may be made of steel or other suitable material, provided that all of the surfaces which are to engage the electrolyte are thoroughly coated with aluminum or with some other film-forming metal. 95

Figs. 4 and 5 show the application of my invention to electrolytic cells of the tray-plate type. The cell illustrated therein comprises a series of plates 35 composed of aluminum or other film-forming material inclosed within a tank 36 and supported upon vertical sets of spacers 37 which are similar in construction to the spacer sets 7, 8, 9 and 10 of the form of device shown in Figs. 1, 2 and 3. As shown, six sets of spacers 37 are employed, and each of the trays 35 is provided with a centrally located frusto-conical indentation 38 having three symmetrically spaced openings 39 of proper size to receive the screw-threaded projections of the spacers 40 composing the sets 37 and similarly spaced larger openings 40 of larger diameter than the spacer sets, the arrangement of spacers and plates being similar to that described above in connection with the vertical form 110 of plates. Suitable terminals 41 are secured to any two of the spacer sets 37 which are associated with the plates of opposite polarity. 115

The structural details which I have shown and described are well suited for embodying 120 the principles of my invention, but it is to be understood that this structure may be variously modified without departing from the spirit and scope of my invention, and I desire, therefore, that no limitations shall be 125 imposed upon my invention except such as are indicated in the appended claims.

I claim as my invention:

1. An electrolytic cell comprising a plurality of substantially vertical plates of film- 130

- forming metal, a plurality of multi-part members extending through said plates from side to side and serving to maintain them in alternately connected and spaced relation.
2. An electrolytic cell comprising two sets of plates of film-forming metal maintained in alternately connected and spaced relation, and spacing members, adapted for screw-threaded engagement with one another, for rigidly clamping the plates composing each set of alternate plates, the said spacing members extending through openings in the plates composing the other set.
3. An electrolytic cell comprising two sets of substantially vertical plates of film-forming metal maintained in alternately connected and spaced relation, and spacing members in screw-threaded engagement with one another and forming continuous horizontal supports for rigidly clamping the plates composing each set of alternate plates.
4. An electrolytic cell comprising a plurality of plates of film-forming metal maintained in alternately connected and spaced relation, and spacing members having screw-threaded projections and tapped openings, whereby a plurality of the said spacing members are secured together, forming a substantially continuous rod and rigidly clamping the plates composing one set of alternate plates.
5. An electrolytic cell comprising a plurality of plates of film-forming metal maintained in alternately connected and spaced relation, and spacing member having screw-threaded projections and tapped openings, whereby a plurality of the said spacing members are secured together, forming a substantially continuous rod and rigidly clamping the plates composing one set of alternate plates, the said spacing members composing each set or rod extending through openings in the plates composing the other set.
6. An electrolytic cell comprising a container, a plurality of plates of film-forming metal, multi-part members for rigidly maintaining said plates in spaced relation, means for removably supporting the said plates in the said container, and means for preventing endwise and sidewise movement of the said multi-part members in the said container.
7. An electrolytic cell comprising a container, a cover therefor, a plurality of plates of film-forming metal secured to the said cover, multi-part members for rigidly maintaining the said plates in spaced relation, and means associated with the sides of the said container and coöperating with the ends of said multi-part members to prevent movement of the said plates with respect to the container.
8. An electrolytic cell comprising a container, a cover therefor, a plurality of plates of film-forming metal secured to the said cover, multi-part members for rigidly maintaining the said plates in spaced relation, and a plurality of cleats attached to the sides of the said container and coöperating with the ends of said multi-part members to prevent movement of the said plates with respect to the container.
9. An electrolytic cell comprising a container, a cover therefor, a plurality of plates of film-forming metal secured to the said cover, spacing members connected together in continuous sets or rods for rigidly clamping the plates in two sets of alternate plates, the spacing members composing each set or rod being in clamping engagement with the plates composing one set and extending through openings in the plates composing the other set, and a plurality of cleats attached to the sides of the said container and coöperating with the said sets of spacing members to prevent movement of the said plates with respect to the said container.

In testimony whereof, I have hereunto subscribed my name this 30th day of Dec., 1916.

JOHN COULSON.
